U.S. Appl. No. 29/508,242, filed Nov. 4, 2014, by Wainwright et al.
(Continued)*Primary Examiner* — Ian Simmons*Assistant Examiner* — Mark Cavanna(74) *Attorney, Agent, or Firm* — Goodwin Procter LLP(57) **CLAIM**

The ornamental design for a filtration device, as shown and described.

DESCRIPTION

FIG. 1 is a top perspective view of a filtration device;
FIG. 2 is a front elevation view thereof;
FIG. 3 is a side elevation view thereof;
FIG. 4 is a top plan view thereof;
FIG. 5 is a bottom plan view thereof;
FIG. 6 is a cross-sectional view thereof taken along line 6-6
in FIG. 4; and,
FIG. 7 is a bottom perspective view thereof.
